US00D892306S

(12) **United States Design Patent** (10) **Patent No.:** **US D892,306 S**
(45) **Date of Patent:** **** Aug. 4, 2020**

(54) **SURGICAL MASK**

(71) Applicant: **Revolutionary Medical Devices, Inc.**,
Tucson, AZ (US)

(72) Inventors: **Thomas M. Reilly**, Tucson, AZ (US);
Michael J. Pedro, Brooklyn, NY (US);
Steven H. Cataldo, New York, NY
(US); **Ryan G. Redford**, Tucson, AZ
(US); **David M. Kane**, Tucson, AZ
(US)

(73) Assignee: **Revolutionary Medical Devices, Inc.**,
Tucson, AZ (US)

(**) Term: **15 Years**

(21) Appl. No.: **29/689,383**

(22) Filed: **Apr. 29, 2019**

Related U.S. Application Data

(63) Continuation of application No. 29/583,554, filed on
Nov. 7, 2016, now Pat. No. Des. 848,606.

(51) **LOC (12) Cl.** **29-02**

Bockius LLP

(57) **CLAIM**

The ornamental design for a surgical mask, as shown and
described.

DESCRIPTION

FIG. 1 is a front elevational view of a surgical mask showing
our new design;

FIG. 2 is a rear elevational view thereof;

FIG. 3 is a right side elevational view thereof;

FIG. 4 is a left side elevational view thereof;

FIG. 5 is top plan view thereof;

FIG. 6 is a bottom plan view thereof; and,

FIG. 7 is a top perspective view thereof.

The broken lines in the drawings illustrate portions of the
surgical mask that form no part of the claimed design.

1 Claim, 4 Drawing Sheets
